UNITED STATES PATENT OFFICE.

DANIEL C. TEETOR, OF TIPTON, INDIANA.

PISTON RING.

Application filed February 25, 1926. Serial No. 90,560.

My invention relates to piston rings that employ channels extending therethrough to establish communication between the interiors and exteriors of the rings for the 5 passage of lubricant to the ring containing grooves in the pistons from whence the lubricant is returned to the interiors of the pistons and the crank cases in communication with the piston interiors.

10 In carrying out my invention, I provide two parallel series of contiguous channels that are elongated and distributed circumferentially of and pass through the ring, the channels of each set being in staggered 15 relation to the channels of the other, one end wall of each channel of each set converging toward the other end wall of such channel and crossing an end wall of a contiguous channel in the other set.

20 In the preferred embodiment of the invention, the channels of each series are disconnected in the ring itself although lubricant may flow between the channels of both 25 and each series in the actual use of the ring, the lubricant flowing between the channels through the space between the ring and the cylinder and through the space between the ring and piston. In the ring of my invention, the volume of lubricant conducting 30 space passing therethrough is increased without weakening the ring, integral bridge portions of the ring at the inner cylindrical side thereof extending widthwise of the ring from flat face to flat face. Both end walls of each 35 channel of one set desirably cross the adjacent end wall of two contiguous channels in the other set whereby such an integral bridge portion is provided between each of the two contiguous ends of adjacent channels in the 40 two series, a construction which renders the ring substantially inflexible widthwise, especially at its inner cylindrical side.

The invention will be more fully explained 45 in connection with the accompanying drawing in which Fig. 1 is a view partially in section and partially in elevation illustrating a ring of my invention, a piston furnished with the ring and a cylinder in which the piston reciprocates; Fig. 2 is a sectional view on line 2-2 of Fig. 1; Fig. 3 is a sectional view on line 3-3 of Fig. 4; Fig. 4 is 50 a view of a part of the structure appearing in Fig. 2, but on a larger scale; and Fig. 5 is a perspective view of a part of the ring 55 with portions shown in section.

My invention is of particular service in

connection with internal combustion hydrocarbon engines, though the invention is not to be thus restricted.

The engine cylinder 1 may be of any suitable type, the engine cylinder usually communicating at its inner end with a crank case containing a bath of lubricating oil from which working parts of the engine are supplied. The piston 2 is of any suitable or 60 usual form, having one or more annular piston ring grooves 3, 4 that receive piston rings 5, 6. The piston ring groove 4 is nearest the crank case and this groove contains a piston ring of my invention, it being unnecessary to provide such a piston ring in the other piston ring grooves of the piston. The innermost piston ring 6 is formed with two parallel series of contiguous channels, channels 7 being included in one series and channels 8 in the other. These channels are elongated circumferentially of the ring and are distributed circumferentially of the ring and extend from the inner cylindrical side of the ring to the outer cylindrical side there- 70 of, whereby passages for lubricant are afforded through the ring to convey lubricant between its outer and inner cylindrical sides. 75

The channels of each set are in staggered 80 relation to the channels of the other and the end walls of each channel of one set converge inwardly and cross the adjacent end walls of two contiguous channels in the other set. Integral bridge portions 9, extending widthwise of the ring, are left upon 85 the inner side of the ring and each between the contiguous ends of two contiguous channels in the two series, the ring thus being sufficiently solid and massive at its inner side to be there inflexible. Tapering bridge 90 portions 10 are also left, these tapering bridge portions intervening between the contiguous channels in each series. The bridge portions 10 between the channels of each 95 series preferably terminate at the outer cylindrical side of the ring so as to prevent the channels in such series from having direct communication by reason of any formation of the ring, these bridge portions diverging toward and to the inner cylindrical 100 side of the ring so as to constitute a broad support for the adjacent circumferentially extending wall of the channel in the other series to reduce the flexibility thereof and to maintain the massiveness of the ring as 105 far as it is possible consistent with the functions that the ring is to perform. By virtue 110

of the close endwise proximity of the channels in each series, no passages are required in the exterior cylindrical side of the ring to bring the channels into communication, there being sufficient outward and circumferential flow of lubricant at the ends of the channels to properly lubricate the exterior ring surface portions between the adjacent channels of each series. The channels define inwardly converging spaces in which tapering bodies of lubricant are contained, these lubricant bodies being constantly replenished by lubricant flowing into the channels that is caught from the inner surface of the cylinder to replace the lubricant which flows through the reduced inner ends of the channels at the interior of the ring, the channels, by virtue of their shape, sufficiently retarding the inward flow of the lubricant to permit it to properly perform its function. The outer or apex ends of the bridge portions 10 serve to cut through the lubricant or oil film with ease to promote the flow of the lubricant between the channels of each series and over the unchan-

neled portions of the outer cylindrical side of the ring. The tool employed for forming the channels is desirably a milling tool in the form of a disc wheel having suitable cutting teeth upon its periphery and of a 30 diameter to produce the desired converging of the end walls of the channels.

Having thus described my invention, I claim:

A piston ring having two parallel series 35 of contiguous and disconnected channels that are elongated and distributed circumferentially of and pass through the ring, the channels of each set being in staggered relation to the channels of the other, the 40 end walls of each channel of one set converging inwardly and crossing the adjacent end walls of two contiguous channels in the other set, thereby to provide a plurality of 45 spaced solid bridge portions extending from end to end of the ring parallel to the axis of the latter.

In witness whereof, I hereunto subscribe my name.

DANIEL C. TEETOR.
